UNITED STATES PATENT OFFICE.

ROBERT W. BOSTWICK AND GRANT W. BOSTWICK, OF DETROIT, MICHIGAN.

DISAPPEARING BED.

1,300,695.

Specification of Letters Patent. Patented Apr. 15, 1919.

Application filed August 17, 1918. Serial No. 250,376.

To all whom it may concern:

Be it known that we, ROBERT W. BOSTWICK and GRANT W. BOSTWICK, citizens of the United States, residing at Detroit, in 5 the county of Wayne and State of Michigan, have invented certain new and useful Improvements in Disappearing Beds, of which the following is a specification.

Our invention relates to improvements in 10 disappearing beds, and more particularly to beds of the class adapted to be collapsed or folded and stored within a receiving space or recess below the level of the floor of a room. It has for its object to provide 15 means for easily and quickly raising or lowering the bedstead together with the covering doors and other parts, whereby to provide when erected a head and foot board which when lowered to the general level of 20 the floor will inclose the entire structure, compactly within the space, and embodies actuating mechanism combined with one of said doors for raising and lowering the mechanism.

25 The invention also embodies holding and locking mechanism insuring the positive positioning and maintenance of parts, together with other features of construction and operation as shall be more fully hereinafter described.

In the drawings,

Figure 1 is a longitudinal vertical sectional view illustrating the apparatus with the bedstead and covering head and foot 35 boards erected;

Fig. 2 is a transverse sectional view indicated by the line II, II of Fig. 1;

Fig. 3 is a cross sectional view corresponding to the transverse plane of Fig. 2, 40 but showing the parts collapsed and lowered below the floor level;

Fig. 4 is an enlarged sectional detail view showing the lever actuated operating mechanism as mounted on the foot board and indicated by the section line IV, IV of Fig. 2;

Fig. 5 is a similar sectional detail view showing the locking mechanism for the bedstead when erected; and

Fig. 6 is a transverse sectional diagrammatic view showing the head board as erected and the cable connections for the bedstead. Referring to the drawings, we provide a receiving and inclosing body A bounded within the vertical depth of the 55 floor between the ceiling construction below and the floor level above, and within sur-

rounding flooring joist members 2, of suitable rectangular formation and size to receive the various portions of the bedstead and its parts when lowered, as in Fig. 3. 60

The several portions of the construction are suspended when lowered, and maintained when raised by head board 3 and a foot board 4, each of which is hinged at 5 by suitable hinges to the underframe construction, as will be readily understood. The head board and foot board are each suitably strengthened and braced by cleats or battens 6 and trusses 7 having suitable tightening devices, as turn-buckles 8, 70 whereby to maintain the boards in continuous efficient condition.

The bedstead B is of any suitable construction, preferably composed of rectangularly arranged framing members of structural form as angles 9, forming the side members of the bedstead, and transverse terminal angle members 10 forming its end framing members.

The bedstead as thus constructed is adapted to receive and support any suitable spring mattress and bedding, as will be clearly apparent without further description. The bedstead B is designed to be raised by sets or pairs of cables 11, 11 and 85 12, 12, four in all, which are wound upon the periphery of a grooved drum or sheave 13 incorporated with or forming a part of a gear wheel 14 in mesh with an actuating pinion 15, each of which is mounted for operation upon the inner face of foot board 4. The sheave gear 13-14 is suitably journaled at 16, Fig. 2, and pinion 15 is preferably mounted by rolling bearings 17 around the securing stud center 18, and upon the face of 90 a supporting hub plate 19, secured against the inner face of the foot board. Pinion 15 is actuated by a crank lever 20 having a squared stud 21 projecting into a receiving socket in the outer center of pinion 15, and 100 is preferably made removable by providing it with a securing set screw 22, as clearly shown in Fig. 4. By this means, crank 20 may be quickly adjusted or removed for operation.

105 Cables 11, 11 and 12, 12 are fixedly secured by their terminals to sheave 13, and pass in opposite directions therefrom around guiding and supporting sheave wheels 23 secured by their housing plates to the inner face of 110 the foot board at each side of the main sheave. Cables 12, 12, pass downwardly and

are secured as at 24 to cast iron brackets 25 which are rigidly riveted to a transverse angle member 10 at the foot portion of the bedstead (see Figs. 1, 2 and 5).

- 5 Brackets 25 are constructed in the manner shown in Fig. 5, whereby to provide a round bearing portion for the cable, avoiding cutting or abrasion. Similar brackets are secured to the opposite or head end of the 10 bedstead, to which are secured in the same manner, the terminals of cables 11, 11, which support the other end, and, with cables 12, raise and lower the bedstead evenly. Cables 11, which are considerably 15 longer than cables 12, pass downwardly from sheaves 23 around guiding sheaves 26 secured by their housings at each endmost corner of the cavity, to a flooring board bottom 27, as clearly shown in Fig. 1. 20 Cables 11 continue upwardly and pass over supporting and guiding sheave wheels 28, and then downwardly therefrom, in the same manner as cables 12 pass downwardly from sheaves 23 at the opposite end, and are 25 secured to the brackets 25 at the head end of the bedstead, as indicated at 29.

Rollers 25^a are preferably journaled in brackets 25 or in any other suitable bearings at the four corners of the bedstead, and 30 assist in reducing friction by action against the outer battens 6 of the head and foot board.

By this means, it will be seen that as 35 sheave 13 is rotated in one direction, it will raise the bedstead evenly to its highest position, indicated in Figs. 1 and 2, and will, when reversed, lower it to its nested position, as in Fig. 3.

For the purpose of covering over the side 40 spaces of the main cavity A, we provide a pair of longitudinally arranged cover boards 30, 30 hinged at 31 to the inner framing construction and which are connected by cables 32, 32, to the end members 10, 10, 45 of the bedstead. An intermediate cover board 30^a is also suspended by cables 32^a from the bedstead, in the same manner, filling the intervening space.

By this means, when the bedstead is 50 raised, the boards 30 and 30^a will be likewise raised to the position shown in Fig. 2, parallel with the general floor surface, and will be lowered to the position shown in Fig. 3 by gravity when the bedstead is lowered. 55 These boards or platforms completely obscure the pit, assist in deadening any noise from below, and also provide a fire check. Some or all of said platforms may be omitted if desired.

60 Cables 11 and 12 are connected by a suitable link 33 to single cables 34, one above and the other below, each fitting into its particular groove around the sheave wheel 13, the circumference of which is of ample 65 dimensions to insure sufficient cable travel

for complete raising and lowering in less than one complete revolution of the sheave.

Head board 3 and foot board 4 are, when erected, fixedly held in position by bracing bars 35 pivoted at 36 at each side portion of the cavity A, to suitable bearings thereon, and provided with retracting tension springs 37, connected at 38 to the inner shortened arm of brace 35 and at 39 to a holding bracket respectively, as clearly 75 shown in Fig. 1.

The outer ends of brace arms 35 are turned at right angles providing a bearing and locking terminal rod 40 which, when the head and foot boards are erected, is inserted in a holding clevis or bracket 41, a series of four such brackets being provided at suitable positions along the under edge portion of the head and foot boards respectively. Brace arms 35 are also in effect 85 levers which assist in the raising of the head and foot boards, and also in the easy lowering of the same, by action of springs 37.

Mounted in upwardly extending journal 90 bearings or brackets 42, on cross members 10, 10, of the bedstead, is a transverse rod 43 provided at each end with a fixedly secured locking arm 44 adapted to be thrust out across the terminal 40 of brace rod 35, 95 whereby to fixedly hold the same in position, and also partly assist in supporting the bedstead. Rod 43 is provided, between locking arms 44, with a lever arm 45 to which is connected, at each end, a cable 46. 100 Said cable passes around the bearing roller 47 and at the middle, each cable is connected by spring 48, the cable strands and spring being thus located closely adjacent the general supporting level for the mattress. The weight of the occupant on the mattress, supplementing the tension of spring 48, tends to pull down on each lever arm 45 and to hold the locking arms 44, 44, 105 in outwardly thrust position, as in Fig. 5. 110 When such tension is relieved, upon removal of the weight rocking arms 44 are automatically retracted by springs 49 engaging shorter lever arms 50 formed integral with the holding portion of lever 45, throwing 115 arms 44 backwardly from engagement with rod 40.

The construction and operation of the invention will be readily understood and appreciated from the foregoing description, 120 and especially by those familiar with and accustomed to the use of disappearing beds. It provides an extremely compact and self-contained construction, easily capable of being quickly collapsed or erected, and is 125 composed of comparatively few parts. It is continuously reliable in that it provides against possibility of collapse or failure under strain, and is well adapted to the objects in view.

The invention may be variously changed or modified in proportions, design, or structural details by the skilled mechanic, but all such are to be considered as within the scope of the following claims.

What we claim is:

- 5 1. In a collapsible bedstead in combination with a recessed floor, a head and foot board adapted to be lowered to the floor level and to be erected at right angles thereto, a bedstead, raising and lowering mechanism therefor carried by the head and foot boards and provided with actuating mechanism mounted on one of said boards, and spring controlled locking and bracing mechanism for fixedly engaging and holding the bedstead and head and foot boards respectively in erected position. 30
- 10 2. In a collapsible bedstead, in combination with a recessed floor, a head and foot board adapted to be lowered to the floor level and to be erected at right angles thereto, a bedstead, raising and lowering cables therefor carried by the head and foot boards, actuating mechanism therefor mounted on one of said boards, and spring actuated locking and bracing mechanism adapted to engage the bedstead terminals and the head and foot boards respectively. 35
- 15 3. In a collapsible bedstead, in combination with a recessed floor, a head and foot board adapted to be lowered to the floor level and to be erected at right angles thereto, a bedstead, raising and lowering cables therefor carried by the head and foot boards, actuating mechanism therefor mounted on one of said boards, and supporting and bracing levers adapted to engage the bedstead and foot boards. 40
- 20 4. In a collapsible bedstead, in combination with a recessed floor, a head and foot board adapted to be lowered to the floor level and to be erected at right angles thereto, a bedstead, raising and lowering cables therefor carried by the head and foot boards, actuating mechanism therefor mounted on one of said boards, and spring actuated supporting and bracing levers adapted to engage the bedstead and foot boards. 45
- 25 5. In a collapsible bedstead, in combination with a recessed floor, a head and foot board adapted to be lowered to the floor level and to be erected at right angles thereto, a bedstead, raising and lowering cables therefor carried by the head and foot boards, actuating mechanism therefor mounted on one of said boards, and supporting and bracing levers having locking terminals adapted to engage co-acting portions on the head and foot boards and the bedstead respectively. 50
- 30 6. In combination with hinged head and foot boards each having receiving sockets, pivoted spring actuated levers adapted to
- 35 press the boards upwardly and having terminals adapted to engage said receiving sockets, and separately mounted spring retracted locking arms adapted to engage said terminals and hold them in said sockets. 30
- 40 7. In combination with hinged head and foot boards each having receiving sockets, and a vertically adjustable bedstead, pivoted spring actuated levers adapted to press the boards upwardly and having terminals 75 adapted to engage said receiving sockets and the bedstead respectively and to hold the same in erected position.
- 45 8. In combination with hinged head and foot boards each having receiving sockets, and a vertically adjustable bedstead provided at its ends with locking latches, pivoted spring actuated levers adapted to press the boards upwardly and having terminals adapted to engage said receiving 80 sockets and latches respectively and to hold the boards and bedstead in erected position.
- 50 9. In combination with head and foot boards, and supporting arms therefor having locking terminals, a vertically adjustable 90 bedstead having locking latches at each end adapted to engage said terminals, and a depressible connection extending longitudinally of the bedstead connected to opposite latches adapted to maintain them in hold- 95 ing engagement.
- 55 10. In combination with head and foot boards, and supporting arms therefor having locking terminals, a vertically adjustable bedstead having locking latches at each 100 end adapted to engage said terminals, and a depressible connection embodying a tension spring extending longitudinally of the bedstead adjacent its supporting level connected to opposite latches and adapted to maintain 105 them in holding engagement.
- 60 11. In combination with the head and foot boards of a collapsible bedstead each having a holding socket, and bracing arms having co-acting terminals therefor, a bedstead frame provided with pivoted latches adapted to engage over said terminals, and spring actuated mechanism connected with said latches adapted to hold the same in engagement with said terminals. 110 115
- 65 12. In combination with the head and foot boards of a collapsible bedstead each having a holding socket, and bracing arms having co-acting terminals therefor, a bedstead frame provided with pivoted latches 120 adapted to engage over said terminals, spring actuated mechanism connected with said latches adapted to hold the same in engagement with said terminals, and oppositely acting springs for retracting said 125 latches.
- 70 13. In combination with a vertically adjustable bedstead, and an apertured floor providing a receiving recess therefor, hinged cover boards at each side of said recess, an 130

intermediate loosely located cover board, and means flexibly connecting all of said cover boards with the bedstead.

14. In combination with the head and foot boards of a collapsible bedstead, and a mattress supporting frame; a winding drum mounted on one of said boards, and cables leading therefrom in opposite directions, guiding and supporting sheaves at each side
- 10 beyond the winding drum, a branch cable connected with each of said cables and with

one end portion of the mattress frame, a branch cable connected with each of said cables and with the other end portion of the mattress frame and guiding and supporting 15 sheaves for said last named branch cables below the mattress frame and above its other end respectively.

In testimony whereof we hereunto affix our signatures.

ROBERT W. BOSTWICK.
GRANT W. BOSTWICK.
